UNITED STATES PATENT OFFICE.

JOHN J. ROBERTS, OF LOUISVILLE, KENTUCKY.

ELECTRICALLY-DRIVEN RECIPROCATING TOOL FOR RIVETING, CALKING, STONE-CUTTING, ETC.

Application filed October 25, 1920. Serial No. 419,469.

To all whom it may concern:

Be it known that I, JOHN J. ROBERTS, a citizen of the United States, residing at Louisville, in the county of Jefferson and 5 State of Kentucky, have invented new and useful Improvements in Electrically-Driven Reciprocating Tools for Riveting, Calking, Stonecutting, Etc., wherein new and useful designs in the construction of electrically- 10 driven hammers and other reciprocating implements have been devised and new and useful means for operating and controlling said reciprocating devices have been invented. 15 The objects of my invention are,—(1) to design and construct an electrically driven hammer operative on either the direct or the alternating current with greater convenience and less expense than is now possible 20 with an air-driven hammer of equal working power. (2) to devise a novel hammer head provided with guide rails and a tappet lug and adapted in normal operation to be driven a predetermined distance back and 25 forth in straight lines; (3) to provide suitable means adapted to engage said guide rails and thus to hold the hammer head in its operative position; (4) to design unique and practical motor-driven means to be 30 placed adjacent said hammer head and adapted in normal operation to engage said tappet lug intermittently so as to force the hammer head upward its predetermined distance and then to release the lug again; (5) 35 to provide a spring and auxiliary means adapted to be set in the upward movement of said hammer head so as to force the head downward again in a free normal stroke, as said tappet lug is released, which completes 40 the reciprocating movement of said hammer head; (6) to construct for an electric riveting hammer a nozzle and a rivet set adapted to fit therein and receive the blows of the hammer head, also auxiliary means for se- 45 curely retaining the rivet set with a certain slight longitudinal movement in the nozzle in which spring-pressed means always holds the set in its operative position; (7) to de- 50 sign and develop for an electric tool a manually operative switch adapted to close the electric circuit in said electric tool whenever pressure enough is exerted upon the handle of tool to push it normally to its work; (8) to provide suitable means for dis- 55 sipating the internally generated heat units

as rapidly as they are generated in normal operation, so that the electric hammer may operate continuously at a desirable temperature; and (9) to design and construct for an electric hammer an operative mechanism comprising a hammer head and its actuating and coacting parts all adapted to lift the hammer head and to strike the blows with great rapidity and with a minimum of external vibration to the operator, the hammer head with its co-acting parts being adapted to deliver its stroke while entirely free from mechanical connection with the electrically driven parts thereof. 60

All these objects are attained in the present invention, and the electrically driven reciprocating tool illustrated in the accompanying drawings which form a part of this specification, is a practicable apparatus embodying the aforesaid novel means and other new and useful details of construction, arrangement and combination of parts, all of which together with their functions will be described in detail with reference to said drawings, and will be definitely pointed out 65 in the claims that follow the description. 70

In said drawings, Fig. 1 is a longitudinal section of my electric hammer and casing along the axis, with the handle, one tie rod, a part of the tail cap, one guide post and the moving parts of the hammer showing in elevation, the other guide post and tie rod having been removed by the section. Fig. 2 is a detail of the reciprocating mechanism and frame thereof showing a fragment of the casing in section and the other parts of the mechanism and frame, and also fragments of the nozzle and the rivet set, in elevation. 75

This invention has been developed for general use where an efficient reciprocating power tool large or small is desirable, and may be made in differently shaped casings for different uses without departing from the principle of the invention. 80

With the general purpose and the special objects aforesaid in view, I will now describe my invention in detail, pointing out and explaining the uses and the operations of the various parts and combinations thereof throughout my invention, as illustrated in the drawings hereinabove specified, in which similar letters and characters refer to similar parts throughout the several views. 85

In Fig. 1 the numeral 1 represents my electrically driven hammer in its casing. 100

2 points out the field iron and 3, the armature of the electric motor part of the hammer; and 4 indicates the hammer casing.

The automatic switch.

5 As shown in Fig. 1, switch knife 27 is hinged at pintle 26^a in pintle post 26^a, a part of the base of which is used as a binding post for circuit wire 26 as it comes through 10 a hole in casing 4; and the switch knife 27 appears standing out of its clip 27^a, a part of the base of which is used as a binding post for circuit wire 27^b from said clip 27^a to field coil 27^x; and the switch is open as 15 the knife 27 stands out of the clip 27^a, having been pushed out of said clip 27^a by means of the helical switch spring 30 under compression in its insulating socket 29, the upper end of which is seen to be slotted to 20 allow the movement of the knife 27. On the upper edge of knife 27 rides push pin 33^a securely fixed in the insulating block 33, the inner part of which is made readily removable with a punch passed through the threaded hole in base 33^b now closed with the threaded stopper 33^c.

Inside the upper end of casing 4, tool handle base 32 with its tubular extension 32^a is slidably inserted and held in place by 30 means of the annular cap 31 which is fastened to casing 4 with screws 31^a; and just below said tubular extension 32^a inside casing 4 is fixed the insulating disc 28, down through the central part of which is screwed 35 the inner guide tubing 29^a adapted to fit closely into the outer guide tubing 34 to cause the handle base 32 with its tubular extension 32^a to slide in straight lines without rocking when the handle 32^c is pushed downward to close the switch. Tube 34 is also slotted.

It can now be readily seen that when 45 wires 25 and 26 are energized and handle 32^c is pushed downward hard enough to overcome switch spring 30, push pin 33^a riding on the upper edge of switch knife 27 forces the switch knife into its clip 27^a, thus closing the motor circuit, and the current running in on wire 26 would pass through binding post and knife post 26^a, knife 27, clip 27^a, and its binding post, wire 27^b, coil 27^x, wire 27^c and its post to commutator brush 5; thence through armature coils 3, brush 5^a, wire 25^a and its post, field coil 25^x and out 50 along circuit wire 25, thus operating the motor so long as the slidable handle part is kept pressed downward hard enough to hold the knife switch closed. But when the handle is released, switch spring 30 forces 55 upward knife 27 out of its clip 27^a, the circuit to the motor is opened and the motor stops. It is seen now that as the knife 27 is forced upward, it in turn forces upward the push pin 33^a and its base, parts 32 and 60 34 to the upper end of its slide, as shown

in Fig. 1 in which position it is held by spring 30 with the motor circuit open until the handle is pushed downward again to operate the motor. The characters 2^c, 2^a indicate ventilation holes to the switch 70 chamber.

The electric motor.

Next below the switch mechanism in casing 4 is installed the tool motor, the field iron 2^x and coils 25^a, 27^x being secured to the casing 4 by means of the screws 2^a, 2^b, Fig. 1, and the armature 3 being journaled at the upper end in the bushing 24 in plate 23 which is fixed in the casing 4 by means of screws 23^a, 23^b; while at the lower end, the armature is journaled in the bushing 6^a fastened in journal plate 6^b. The motor is series wound, with its commutator brushes set opposite each other, being bipolar and 85 adapted to operate on either the D. C. or the A. C. circuit. On the armature shaft, Fig. 1, is fixed a centrifugal fan 3^a which forces the heated air out of the motor section through the vent holes 2^b, 2^x, etc., the cool air being taken in at the vent holes 2^b, 2^x, etc., above. The return of the heated air to the motor parts is effectually prevented by the deflection disc 3^b fixed in the casing 90 between the motor and the centrifugal fan 3^a. The lower end of the shaft of armature 3 carries the pinion gear 6 just below its bushing 6^a.

The reciprocating mechanism.

In the lower section of tool casing 4 is installed my reciprocating mechanism and its frame. The head cap 16 and the tail cap 17 are parallel disc plates tied together rigidly with the two tie rods 22, 22 and with 105 the two guide posts 21, 21, Fig. 2. Both the tie rods 22, 22, and the guide posts 21, 21, are screwed into head cap 16 at right angles to the disc; then they pass through tail cap 17, being collared and secured by 110 means of nuts 22^a, 22^b and 21^a and 21^b, Fig. 2. Within this rigid frame the reciprocating mechanism of my electric hammer is mounted. The hammer head 20 is provided with a spindle 20^a adapted to pass up 115 through plate 16 and to hold in operative position the helical compression spring 20^b which abuts plate 16 and hammer head 20. Figs. 1 and 2. The hammer spring 20^b is adapted to be set whenever the hammer head 120 is pushed upward and to force the hammer head back downward again when the head is released from its upward pressure. Hammer head 20 carries on its inner side a rigid tappet lug 20^c on which is movably fixed a 125 thick sleeve 20^d adapted to rotate easily on said lug. The hammer head 20 is also provided on either side with parallel guide rails 20^e, 20^f, rigidly fastened to said head by means of rivets 20^g, 20^h, etc., and adapted to 130

fit slidably into the longitudinal slots 21^a, 21^a in the sides of the guide posts 21, 21, adjacent the hammer head, Figs. 1 and 2. These guide rails 20^a, 20^a and slots 21^a, 21^a 5 in the rigid guide posts 21, 21 are adapted to cause the hammer head 20 with its guide rails 20^a, 20^a to move only in straight lines and in the same plane as it is forced up and down in normal operation over its predetermined 10 operative gap.

Mounted in the reciprocating mechanism frame is a rotatable shaft 9, the upper end of which journaled in head cap 16 carries just above said head cap a pinion gear 11 15 adapted when rotated to rotate said shaft. The lower end of said shaft 9 is journaled in the ball bearing box 10 fixed in tail cap 17, Fig. 1. On shaft 9 near its lower end is mounted a cylindrical cup 8 open at the 20 top while its bottom is centrally bored and provided with hubs projecting inside and outside through which the hub pins 8^a, 8^a are driven to fasten said cup 8 rigidly to shaft 9. The sides of said cup around the 25 upper part have been cut to form a helical incline 14 leading from near the bottom of the cup gradually up to the top to a peak 14^a having on its opposite side a sharp declivity 14^b extending downward to the lowest 30 part of the helical incline 14. Now cylindrical cup 8 when driven by shaft 9, is adapted to rotate with its helical incline 14 always passing under tappet lug 20^a with its rotatable sleeve 20^c; and this rotating 35 movement of the helical incline 14 on cup 8 in normal operation causes sleeve 20^c on tappet lug 20^a to roll up over helical incline 14 to peak 14^a, as seen in Fig. 1, when, as the peak 14^a passes, lug 20^a, 20^c under pressure of spring 20^b, jumps down the declivity 14^b to the lowest part of the incline 14, as seen in Fig. 2; and then starts up the helical incline 14 again. Thus hammer head 20, 40 by means of its tappet lug 20^a, 20^c actuated by the rotating cylindrical cup 8 with its helical incline 14, is lifted up its predetermined distance; and by means of the compression spring 20^b said hammer head, when released by the passing of peak 14^a, is forced 45 downward and delivers its blow in normal operation while entirely free from operative connection with the other electrically driven parts of my hammer. By these means the reciprocating movement of the 50 hammer head in normal operation is effected with great rapidity and with ease on the operative parts; while the external shocks transmitted to the operator are very slight when compared with the external vibratory 55 shocks received by the operator from the internal explosions of compressed air or steam in the air hammer.

In the cylindrical cup 8, on the limb where the sides of the cup are low-cut there is not 60 so much weight as on the opposite limb

where the sides are high-cut; consequently, in the rotation of cup 8, the centrifugal force of these said opposite limbs will not be equal; moreover, as the tappet lug 20^a, 20^c of the hammer head 20 is not being raised throughout the whole cycle of rotation of said cup 8 there is intermittent work being done by said rotating cup. Therefore, to compensate this intermittent work and the unequal centrifugal force from the rotation 70 of the cup's limbs of unequal weight, I have fastened near the upper end of shaft 9 just under head cap 16 a stabilizer consisting of an inverted cylindrical cup 7 of nearly the same weight and shape as cup 8, the bottom 80 of cup 7 being centrally bored and provided with internal and external hub projections through which the pins 7^a, 7^a hold said cup securely to shaft 9. Cup 7 is mounted on shaft 9, having been cut and adjusted and thus adapted to compensate the unequal centrifugal forces of the heavy and the light limbs and also the intermittent work of cup 8 in its cycle of rotation in normal operation. 90

Between plate 6 and head cap 16 is installed the compound gearing 12, 12^a, journaled in said plates, the upper gear 12 being adapted to mesh with pinion 6 on the lower end of the shaft of armature 3, while the lower gear 12^a is adapted to mesh with pinion 11 on the upper end of shaft 9; all of which spur gears together; as seen in Fig. 1, constitute the gear train adapted to drive shaft 9 and its attachments 7 and 8 100 to raise said hammer head intermittently a predetermined distance against the pressure of the main spring 20^b, when the hammer motor is operating. 105

The nozzle and the rivet-set.

On the underside of tail cap 17 the nozzle base 18 is fastened to said tail cap by means of the cap screw 18^a, Fig. 1, and also by means of the threaded nuts 21^b, 21^b, on the lower ends of the guide posts 21, 21 Fig. 2. And out from base 18 projects the fixed part 18^b of the nozzle directly in line with the operative movement of hammer head 20, said fixed part 18^b of the nozzle being 110 provided with a central boring reaching through the base 18 and on directly through the adjacent part of the tail cap 17 under the face of hammer head 20, Figs. 1 and 2. Said boring is adapted to receive any tool bit such as the rivet set 19, 19^a appearing in Fig. 1 partly in section and partly in elevation, whose shank 19^a, a reduced portion, is adapted to reach up through said boring so that its face 19^b can receive the 115 blows of hammer head 20 in its normal operation. Fixed part 18^b of the nozzle is also provided with a short counterboring concentric with the central boring aforesaid; and rigidly pinned to shank 19^a is 120 125 130

collar 19^b which is adapted to settle against the bottom shoulder of the counterbore allowing the shank 19^a to stand a predetermined distance above the inner surface of tail cap 17 to receive the blows of hammer head 20. Said counterbore of the fixed part 18^b is provided with threads; and rivet set 19, 19^a is provided with a heavy sleeve 18^c as seen in Fig. 1 partly in elevation and partly in section. The inner end 19^d of said sleeve is provided with threads and adapted to be screwed into the threaded counterbore of the fixed part 18^b, said sleeve making a close joint and even surface with the fixed part 18^b so that both the fixed part 18^b and the removable part, sleeve 18^c, together constitute the nozzle of my electric hammer. And in the outer end of sleeve 18^c is a shallow counterbore adapted to take in a part of the rivet set head 19 for a predetermined distance, which I will now explain. It is desirable in operation that a tool-bit, such as rivet set 19, 19^a, adapted to be held securely in the nozzle, should have sufficient longitudinal movement therein to enable it to complete its normal work stroke under the impulse of the hammer blow. Such longitudinal movement is provided for in the following manner: Within the counterbore of the fixed part 18^b, between the collar 19^b and the threaded part 19^d of the sleeve 18^c is a clear space along shank 19^a, which is provided with a helical compression spring 19^e partially set, one end of which abuts collar 19^b while the other end abuts the threaded portion 19^d of sleeve 18^c. The process of screwing the sleeve 18^c into the fixed part 18^b of the nozzle compresses spring 19^e hard enough to hold shank 19^a up in its normal position to receive the hammer strokes; and the further compression of the said spring 19^e, under the impulse of the normal blow of hammer head 20, allows an outward working stroke of rivet set 19, 19^a independent of the body of the hammer 1, which is one of the objects of my invention. And the counterbore in the outer end of sleeve 18^c adapted to receive the head 19 of said rivet set under the force of spring 19^e, allows a predetermined amount of longitudinal movement of head 19 without the exposure of the inner shoulder of the head beyond the end of sleeve 18^c, which would endanger the fingers of the operator in making a hand hold on the nozzle.

In Fig. 1 may be seen hammer head 20 at its maximum height, with its lug 20^a, 20^c on the peak 14^a about to jump down the declivity 14^b to a place just above the lowest part 15 of the helical incline 14, in which lowest position said lug may be seen in Fig. 2, while hammer head 20 rests in its lowest position with its face in contact with the upper surface of tail cap 17, hav-

ing forced the shank 19^a downward to the limit of its working stroke with its face 19^e down in the same plane with the upper surface of tail cap 17; for it is desirable that the brunt of the hammer head blows in normal operation should fall primarily upon shank face 19^e, while it is in its upper position as it appears in Fig. 1; and when the shank is driven downward to the limit of its working stroke, the residual force of the hammer head should fall upon tail cap 17, as illustrated in Fig. 2. Thus the stroke of hammer head 20 is always completed and stopped before the tappet lug 20^a, 20^c comes down in contact with the part 15 of the helical incline 14.

Having thus described the features of my invention, the operation, construction, arrangement and combination of its parts, what I claim in my invention as new and useful and what I desire to have outlined and specified in Letters Patent, I have herein below set forth specifically in the following claims.

Claims.

1. In an electrically driven reciprocating tool provided with a handle, for riveting, calking, stone-cutting, etc., a motor driven by electro-magnetism, an insulated electric circuit to said motor, a manually operative switch in said circuit adapted to be closed by pressure upon the handle of said tool and to be opened automatically by the release of said pressure, combined with a reciprocating member or hammer head, a rotatable cylindrical cup and its rotating shaft adapted to lift said hammer head intermittently a predetermined distance, a spring adapted to force said hammer head down again, a stabilizer fixed to said shaft to compensate the intermittent work of said cylindrical cup, a gear train adapted to drive said shaft from said motor, and a nozzle provided with a long-shanked tool bit slidably fastened therein and adapted to receive the blows of said hammer head in normal operation.

2. In an electrically driven riveting hammer, a rigid casing provided with a handle on its upper end and a tail cap on its lower end, on said tail cap a nozzle adapted to hold the shank of a tool-bit slidably fastened therein, a compression spring in said nozzle adapted to hold said shank in its operative position, a hammer head in said casing adapted to be actuated alternately back and forth in straight lines and to strike hard blows upon the end of said shank, a spindle in the upper end of said hammer head, a compression spring on said spindle adapted to be set with the upward movement of the hammer head and to force the hammer head down again to strike its blow upon said shank in normal operation, parallel guide posts fixed near said hammer

head on either side, longitudinal slots in the adjacent sides of said posts, longitudinally disposed guide rails riveted to said head and adapted to fit slidably into said longitudinal slots and to cause said hammer head to move only in straight lines in normal operation, a rigid tappet lug on the side of said hammer head adapted to be used in lifting said head, a sleeve rotatably fixed 5 on said lug, in combination with a rotatable cylindrical cup provided with a helical incline adapted to rotate under said lug so as to lift said hammer head its predetermined distance intermittently and to release it 10 again in normal operation, a rotating shaft provided with end-thrust ball bearings to carry said cylindrical cup, a stabilizer on said shaft, an electric motor provided with a centrifugal fan to drive said shaft and 15 keep said hammer at a desirable temperature in operation, a circuit to energize said motor and a switch to open and close said circuit by means of the tool handle at the will of the operator, substantially as de- 20 scribed.

3. In an electrically driven hammer provided with rigid frame, an electric motor therein with its energizing circuit, an automatic switch in said circuit, a handle for

said hammer provided with a base slidably fastened in one end of said frame, a guide tube concentrically fixed in said base and extending inwardly, rigid means for slidably engaging said guide tube to minimize the rocking of said base and handle in normal operation, means for closing said switch with the inward movement of said base in the pressing of the hammer to its work, in combination with a hammer head adapted to reciprocate in straight lines, a gear train 40 and co-acting mechanism operative by said motor and adapted to drive said hammer head in one direction, a spring adapted to absorb the momentum of said hammer head as it makes its initial movement and also 45 adapted to drive said hammer head in the other direction, a nozzle at the lower end of said frame adapted to hold in operative position the shank of a tool bit slidably fastened therein, substantially as described. 50

In testimony whereof I have hereunto set my signature in the presence of two witnesses.

JOHN J. ROBERTS.
